JUG

Arthur Lonker, Philadelphia, Pa., assignor, by mesne assignments, to B. T. Babbitt, Inc., New York, N.Y., a corporation of New York

Filed Aug. 29, 1962, Ser. No. 71,489

Term of patent 14 years

(Cl. D58—5)

The dominant features of my design reside in the portion shown in full lines.

I claim:

The ornamental design for a jug, substantially as shown and described.
